(57) **CLAIM**

The ornamental design for a roof truss securement strap assembly, as shown and described.

DESCRIPTION

FIG. 1 is a perspective view of a roof truss securement strap assembly showing my new design;

FIG. 2 is an exploded perspective view thereof;

FIG. 3 is a left side view thereof;

FIG. 4 is a front view thereof;

FIG. 5 is a first cross-section view taken from line 5-5 of FIG. 4;

FIG. 6 is a second cross-section view taken from line 6-6 of FIG. 4;

FIG. 7 is a top view thereof;

FIG. 8 is a bottom view thereof; and,

FIG. 9 is a perspective view thereof shown in its state of use. The broken lines showing the studs in FIG. 9 illustrate the environment of the claimed design and form no part thereof. The remaining broken lines in the drawings illustrate portions of the roof truss securement strap assembly and form no part of the claimed design.
